US0D1078717S

(12) **United States Design Patent** (10) **Patent No.:** **US D1,078,717 S**
(45) **Date of Patent:** **** Jun. 10, 2025**

(54) **RING HOLDER**

(71) Applicant: **Shenzhen Sodi Innovation Technologies Co., Ltd.**, Shenzhen (CN)

(72) Inventor: **Yuelian Liu**, Shenzhen (CN)

(73) Assignee: **Shenzhen Sodi Innovation Technologies Co., Ltd.**, Shenzhen (CN)

(**) Term: **15 Years**

(21) Appl. No.: **29/898,633**

(22) Filed: **Jul. 31, 2023**

(51) LOC (15) Cl. **14-03**

(52) U.S. Cl.

USPC **D14/251**

(58) **Field of Classification Search**

USPC D14/251-253, 447, 217, 250, 356,

(57) **CLAIM**

The ornamental design for a ring holder as shown and described.

DESCRIPTION

FIG. 1 is a front, right and top perspective view of a ring holder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right, and top perspective view of the ring holder in an alternate configuration.

1 Claim, 9 Drawing Sheets
